(57) **CLAIM**

I claim the ornamental design for a laser tag grenade, as shown and described.

DESCRIPTION

FIG. 1 is a top, perspective view of a laser tag grenade showing my design.

FIG. 2 is a bottom, perspective view of a laser tag grenade of FIG. 1.

FIG. 3 is a front elevation view of a laser tag grenade of FIG. 1.

FIG. 4 is a rear elevation view of a laser tag grenade of FIG. 1.

FIG. 5 is a side elevation view of the left side of a laser tag grenade of FIG. 1;

FIG. 6 is a side elevation view of the right side of a laser tag grenade of FIG. 1.

FIG. 7 is a top plan view of a laser tag grenade of FIG. 1; and,

FIG. 8 is a bottom plan view of a laser tag grenade of FIG. 1.

In the drawings, the broken lines depict portions of a laser tag grenade that form no part of the claimed design.
